ABSTRACT OF THE DISCLOSURE

An electrical translator is provided in the form of a matrix. Each crosspoint in the matrix is formed by a variable resistor which can be controlled separately as a switch between stages of high and low conductivity. The variable resistors are formed of amorphous materials which exhibit large variations in conductivity when control potentials are applied.

This invention relates to the control of switching systems comprising conductor matrices interconnected at crossing points and particularly to the control of such switching systems and matrices through the use of electrically controlled variable resistance devices interconnecting the crossing points. More particularly, the invention has application to electrically settable translator and storage matrices.

In the prior art, matrices have been used in translators and in radix converters, i.e. in devices for receiving intelligence encoded in one code, or in one radix, and transmitting it in another code, or to another radix, without changes in substance, except for the possible deletion of some information. Among the more successful of these prior art devices have been translators made of a matrix of conductors, certain of which have been connected together through diodes at points where they cross each other. The diodes have been biased selectively to conduct when signals of the proper polarity and amplitude are applied to them over receiving connections. Similar arrays of magnetic cores connecting input signals to selected outputs have been used as information storage devices.

These prior art translating devices share a common limitation, i.e. they are all relatively inflexible in the sense that they can be made to vary their properties only by making mechanical changes in their connections. As an example of this inflexibility, in order to change the connections between one line and another, as determined by a diode, it has been necessary to remove the diode or replace it with another diode. Similarly, with cores used in a matrix to form a memory, if it is desired to alter the character of the memory device itself, either the nature, the position, or the number of cores must be altered.

It is a primary object, therefore, of the present invention to provide means for electrically changing connections between the cross-points of a matrix made up of electrical conductors.

It is a second object of this invention to provide a matrix of electrical conductors coupled at cross-points through couplings, the electrical characteristics of which may be varied by electric signals.

The foregoing objects and others ancillary thereto are accomplished according to preferred embodiments of this invention by use of translator or speech matrices composed of electrical conductors. In preferred examples, the conductors are coupled at their cross-points by connectors having variable values of resistance. The variations in resistance of the resistors in turn are controlled by the application of certain "setting" potentials which are applied independently of any signals to be routed.

The novel features characteristic of this invention are set forth with particularity in the appended claims. The invention itself, however, both as to its organization and its method of operation, together with additional objects and advantages thereof, will best be understood from the following description of specific embodiments when read in connection with the accompanying drawings, in which:

FIG. 1 is a diagram of a matrix of conductors arranged in accordance with one aspect of the invention,

FIG. 2 is a diagram illustrating another embodiment of the invention, and

FIG. 3 is a block diagram illustrating yet another embodiment of the invention.

Turn now to FIG. 1 for a detailed showing of an embodiment of the invention. The horizontal conductors 1, 2 . . . N and vertical conductors a, b . . . z cross each other to form arrays in a well known manner. At each crossing point such as are found at 1a, 1b, 2a, 2b, etc., a connection is made through a resistor R1a, R1b, R2a, R2b, etc. and a corresponding diode D1a, D1b, D2a, D2b, etc. Fixed biasing potentials may be applied as "priming" potentials on terminals 1, 2, 3 . . . N, or on terminals a, b . . . z, so that the application of additional potentials on selected ones of terminals a, b . . . z or terminals 1, 2, 3 . . . N, respectively, tends to prepare the way for conduction between corresponding horizontal wires 1, 2 . . . N and output leads A, B . . . Z.

Thus far, the description of the operation of the matrix of FIG. 1 is like that of a conventional matrix in which output signals may be supplied on the simultaneous occurrence of signals on a row of conductors and a column of conductors connected through diodes at selected crossings points. However, the circuit of FIG. 1 offers additional possibilities which have not been described previously, since it includes electrically settable variable resistors. FIG. 1 embodies a third set of terminals at T1a, T2a, T1b . . . TNz upon which potentials may be applied to control the electrically settable variable resistors, which may be of the Pearson type (see Patent No. 3,117,013 to Northover and Pearson), at R1a, R1b, R2a, R2b, etc. These additional elements make it possible to introduce wholly new conditions and make possible much more flexible devices. For example, if the variable resistors are Pearson devices they can be made conductive or non-conductive in accordance with a third set of signals, which may represent a selective code. Thus, output signals will be controlled as a result of potentials applied to three sets of conductors, instead of by potentials applied to the usual two sets to determine which of the terminals A, B . . . Z will be graced by output signals.

The embodiment of the invention shown in FIG. 1 may be used as a translator which can accept signals in one code, such as a binary code, and translate them to another code, such as the well known Gray code. The presence of the variable resistors makes possible the introduction of a third set of variables in the form of a third set of input signals so that the translator can be modified by electrical means to translate different codes or to change from one radix conversion to another. This embodiment of the invention may be used to translate called signals, such as telephone numbers, from one form to another in order to route telephone calls in a desired way. It can also be used to control the path of any data supplied in the form of electrical signals in parallel or to extend the speech paths of a switching system.

The embodiment of the invention shown in FIG. 1 may also serve as a memory matrix with Pearson devices at R1a, R1b, R2a, etc. serving as memory elements. In this connection, the multistable character of Pearson devices is employed by switching the Pearson devices between high and low resistance stages by the application of voltage pulses on terminals T1a, T1b, T2a, T2b

... etc. in excess of certain values. Since Pearson devices exhibit a symmetrical relationship, as indicated by diagrams showing their current-voltage characteristics (see Patent 3,117,013), it is possible to drive them in opposite directions so that they function as bistable memory devices with different values of resistance depending upon the polarity and magnitude of the most recent driving signal. In the embodiment of FIG. 1 it is clear, of course, that the diodes D1a, D1b . . . etc. will tend to prevent conduction in any but one direction. The use of diodes for this purpose appears desirable in many cases in order to reduce the requirements placed on the variable resistor devices R1a, R1b . . . etc. It will be apparent, however, that a matrix of conductors like that shown in FIG. 1 can function without diodes providing only that quality control of the variable resistor devices is held at a high level.

An embodiment of another aspect of the invention is shown in FIG. 2 where a matrix of conductors is connected at crossover points through variable resistors R1a, R1b, R2a . . . RNz and diodes D1a, D1b, D2a . . . DNz. It is apparent immediately that FIG. 2 may be distinguished from FIG. 1 by the absence of a third set of signal sources as well as by the presence of a register M and a scanning switch S. The scanning switch and the register in combination may have a sufficient voltage applied between them and over successive crossing points to cause predetermined ones of the Pearson devices R1a, R1b, R2a . . . etc. to switch to a low resistance state. This capability can cause the matrix to be set so that it can function either as a translator for signals which are then supplied from the register or cause it to perform the function of a semi-permanent storage or memory device.

Once a particular group of resistors from among R1a, R1b, R2a, etc. has been made conductive, or less resistive, by actions of the register and the scanning switch, the circuit of FIG. 2 can be used as a matching device to match memories or to function as a semi-permanent translator. When it functions as a matching device, a readout from the scanning switch at a terminal 22 will occur whenever a signal supplied by the register to a particular horizontal, such as horizontal 3, coincides with a low resistance in a resistor, such as R3a, R3b, etc. and also coincides with a setting of the scanning switch to a particular vertical.

The embodiments of the invention disclosed thus far can be used more effectively in some cases with the help of additional components to perform various functions. For example, the embodiment shown in FIG. 2 can be used as illustrated in the block diagram of FIG. 3 to form a matching type store. In FIG. 3, the memory or translating function of FIG. 2 (FIG. 1 would appear to function equally well) is illustrated in block 32 with the vertical lines terminating at A, B, C . . . Z extended to a stepping switch at 34. A register 36 is also connected to the stepping switch 34 through corresponding terminals A', B' . . . Z'. A coded signal may be applied from a terminal 38 to the register. The stepping switch 34 can then be caused to wipe corresponding terminals such as B and B' and a comparison can be made of the resulting signals in a coincidence circuit or an AND gate 40. With this arrangement, an output signal will be supplied at a terminal 42 only when a signal received from 32 corresponds to that stored in the register 36.

Besides providing for additional functions, an arrangement such as that shown in FIG. 3 provides greater flexibility and speed than is possible with circuits corresponding to the diagrams of FIG. 1 or FIG. 2 alone. The block 32, for example, represents a complete translator or memory which may be set or reset independently of the stepping switch 34 or the register 36. Thus it is possible to change the conductivity of various resistors represented by block 32 without interfering with the operation of the remainder of the circuit.

For purposes of illustration, simple blocks have been employed to represent well known circuits which may be used in embodiments of the present invention. For example, an electro-mechanical device has been shown to represent a stepping switch, and a similar device might be used as the scanning switch S, but it will be recognized that an all-electronic circuit of conventional logic circuits could be used to take advantage of the speed inherent in components such as are shown in FIG. 1 and FIG. 2.

It will be recognized from the foregoing that the various embodiments of this invention may function as a memory, as a translator or as a matching translator.

As a memory, a signal applied on a horizontal such as might be represented by terminals T1a, T1b . . . T1z or by terminal 1 of FIG. 1, can be used to stimulate a readout from any previously set verticals over terminals A, B . . . Z, where the verticals may previously have been set over terminals a, b . . . z. FIG. 2 shows an embodiment of the invention which can also function as a memory device. If the equipment of FIG. 2 is used as a memory device, the variable resistors can be set to have a certain "memory" by the register or by coincidence of signals from the register and over terminals a, b, c . . . z. The verticals can then be systematically scanned over terminals A, B, C . . . Z by the scanning switch S.

Considering the operation of embodiments of the invention as a translator, it may be noted that a register such as is shown at M in FIG. 2, set by say, binary or decimal information could select a single horizontal on the basis of the registered information, and then energize the verticals as in the case of the memory.

As a matching translator, each horizontal may be preset to have an input combination (binary, decimal or any other form) and a corresponding output combination. To start a translation, the horizontals are energized one after another by a scanning circuit, but only the verticals on the input section are read and matched against the information for which a translation is desired. When a match occurs, the output information on the matched horizontal is permitted to be read out.

While the principles of the invention have been described above in connection with specific apparatus and applications, it is to be understood that this description is made only by way of example and not as a limitation on the scope of the invention.

What is claimed is:

1. An electrically settable switching device comprising:
a matrix composed of conductors crossing each other at a plurality of crosspoints,
variable resistor means interconnecting each of said crosspoints,
said variable resistor means being settable, in response to the direct application of electrical potentials, to high or low resistance states, and
means connected to receive said potentials for setting each of said variable means to a desired state.
2. An electrically settable switching device substantially as claimed in claim 1, in which:
unidirectional devices are connected in series with each of said variable resistor means.
3. An electrically settable switching device substantially as claimed in claim 1, in which:
each variable resistor means is connected by two separate terminals to two crosspoints, and
said means to receive said potentials for setting each of said variable means includes a third terminal coupled to each variable means.
4. A coordinate switching system comprising:
a plurality of conductors crossing one another,
interconnecting means interconnecting said conductors, said interconnecting means including a bidirectional variable resistor controlled to two different resistance levels by the direct application of potentials, and

means connected to said bidirectional variable resistor to receive said potentials.

5. A coordinate switching system substantially as claimed in claim 4, in which:

said interconnecting means includes a unidirectional device in series with said bidirectional variable resistor.

6. A coordinate switching system substantially as claimed in claim 4, in which:

said means connected to said bidirectional variable resistor to receive said potentials constitutes a separate terminal, and

said interconnecting means includes two additional terminals connecting to separate conductors.

7. A coordinate switching system comprising:

a plurality of conductors arrayed in a matrix to cross one another at crossover points,

interconnecting means for interconnecting said conductors between terminals at said crossover points, said interconnecting means including bidirectional re-

sistor devices responsive to the direct application of potentials to switch their degree of resistance between two states, and

means connected to selectively receive potentials to activate selected ones of said bidirectional devices.

8. A coordinate switching system substantially as claimed in claim 7, in which:

said interconnecting means includes a unidirectional device in series with each of said bidirectional resistor devices.

9. A coordinate switching system substantially as claimed in claim 7, in which:

said means to selectively receive potentials to activate selected ones of said bidirectional resistor devices include terminals distinct from said terminals at said crossover points.

10. An electrically settable switching device comprising:

a plurality of crosspoints, variable resistor means interconnecting each of said crosspoints,

said variable resistor means being settable by the application of voltage to semi-permanent conductive or non-conductive states, and

means connected to receive voltages for setting each of said variable means to a desired state.

11. A coordinate switching system comprising: a matrix composed of a plurality of conductors crossing one another, interconnecting means coupled to interconnect said conductors,

each of said interconnecting means including a voltage controlled bidirectional resistor and a unidirectional device connected in series, and

means for receiving a voltage and applying it to said bidirectional resistor to control the bidirectional device.

12. A coordinate switching system substantially as claimed in claim 11, in which:

said means for receiving and applying a voltage includes a register and switching means.

13. A coordinate switching system substantially as claimed in claim 11, and including matching means for comparing signals received through said bidirectional resistor with signals from another source, said matching means including:

switching means for simultaneous reception of signals from said bidirectional resistor and said another source, and

gating means for comparing said signals received by said switching means to enable determination of coincidence between the signals.
